US00D368470S

United States Patent [19]**Kondo**[11] **Patent Number:** **Des. 368,470**[45] **Date of Patent:** ****Apr. 2, 1996**[54] **ELECTRONIC COMPUTER**

- [75] Inventor: **Osamu Kondo**, Tokyo, Japan
- [73] Assignee: **Kabushiki Kaisha Toshiba**, Kanagawa, Japan
- [**] Term: **14 Years**
- [21] Appl. No.: **17,406**
- [22] Filed: **Jan. 12, 1994**

[30] **Foreign Application Priority Data**

- Aug. 11, 1993 [JP] Japan 5-24454
- [52] U.S. Cl. **D14/106**
- [58] **Field of Search** ..... D14/100, 101, D14/106, 113, 115, 124-127; D18/1, 7, 11, 12; 235/145 A, 145 R; 341/22, 23; 345/104, 156, 168, 173, 901-905, 87; 361/679-686; 364/708.1, 709.04, 709.12; 400/486, 489

[57] **CLAIM**

The ornamental design for an electronic computer, as shown and described.

DESCRIPTION

FIG. 1 is a top, front and right side perspective view of an electronic computer showing my new design;
 FIG. 2 is a front elevational view thereof;
 FIG. 3 is a rear elevational view thereof;
 FIG. 4 is a left side elevational view thereof;
 FIG. 5 is a right side elevational view thereof;
 FIG. 6 is a top plan view thereof;
 FIG. 7 is a bottom plan view thereof;
 FIG. 8 is a front elevational view thereof in closed position;
 FIG. 9 is a right side elevational view thereof in closed position; and,
 FIG. 10 is a plan view thereof in closed position.
